FOOTWEAR HEEL

George W. Cobb, Pacific Beach, Calif.

Application February 21, 1940, Serial No. 320,061

6 Claims. (Cl. 36—35)

My invention relates to a footwear heel, more particularly a footwear heel of special construction for attachment with footwear soles and the objects of my invention are:

First, to provide a footwear heel of this class which is so constructed and arranged in its connection with footwear that it provides a heel of very long wearing capacity and which is very simple and neat in appearance;

Second, to provide a footwear heel of this class which is exceptionally yieldable and provides greater comfort to the feet of wearers thereof, thereby promoting health and well being of said wearers when standing and walking extensively;

Third, to provide a footwear heel of this class which is very simple and easy to attach to footwear in a permanent and secure relation therewith;

Fourth, to provide a footwear heel of this class provided with a novel attaching means for connection with footwear soles;

Fifth, to provide a footwear heel of this class which is positioned in direct contact with the sole of the footwear on which it is secured;

Sixth, to provide a footwear heel of this class which eliminates the usual nail holes in the heel surface of the heel which gather dirt etc.; and

Seventh, to provide a footwear heel of this class which is very simple and economical of construction, efficient, exceptionally durable and which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawing and to the characters of reference thereon which form a part of this application in which:

Figure 1 is a side elevational view of my footwear heel shown secured on a fragmentary portion of a shoe sole; Fig. 2 is a sectional view taken from the line 2—2 of Fig. 1; Fig. 3 is a sectional view taken from the line 3—3 of Fig. 2; Fig. 4 is a transverse sectional view taken on the line 4—4 of Fig. 2; Fig. 5 is a similar view to that as shown in Fig. 4 showing a modification of my footwear heel and Fig. 6 is a sectional view taken from the line 6—6 of Fig. 5 showing a part and portions thereof in elevation to facilitate the illustration.

Similar characters of reference refer to similar

parts and portions throughout the several views of the drawing:

The heel member 1, heel supporting member 2, heel supporting member fastening nails 3, adhesive 4, and the footwear sole 5 constitute the principal parts and portions of my footwear heel and footwear connection.

The heel member 1 is substantially conventional in form except that it is sufficiently thick to provide proper elevated support of the footwear at its heel portion when the upper side of said heel member 1 is secured directly to the footwear sole 5 and eliminating the conventional leather portions of the heel as shown best in Fig. 1 of the drawing. This heel member 1 is preferably made of rubber or other suitable resilient composition and is provided with a recess portion 1a in its upper side, as shown best in Figs. 3 and 4 of the drawing. This recess portion 1a is provided with an angular downwardly and forwardly extending front wall portion 1b and an angularly downwardly and forwardly extending rear wall portion 1c, as shown best in Fig. 3 of the drawing. This recess portion 1a is also provided with downwardly and inwardly extending side wall portions 1d, as shown best in Fig. 4 of the drawing.

Positioned in this recess portion 1a is the heel supporting member 2 which is provided with outer sides which conform with the walls of said recess portion 1a in the heel member 1, as shown best in Figs. 3 and 4 of the drawing. The heel supporting member 2 is preferably wood, but may be of other material and it is secured on the shoe sole member 5 by means of the heel fastening nails 3, as shown best in Figs. 1, 2 and 3 of the drawing. It will be noted that the heel member 1 is secured on the heel supporting member 2 by means of cement or any suitable adhesive material 4 as shown in Figs. 3 and 4. Said adhesive material is applied to the heel supporting member 2 and to the sole 5 around said heel supporting member 2. Said adhesive is applied after the heel supporting member 2 is secured on the footwear sole 5 by means of the heel fastening nails 3. The heel member 1 is then placed on and over the front angular side of the heel fastening member 2 and is then forced over the inclined angular rear end and sides of the supporting member 2 at its angular portions 2a and 1d respectively as shown best in Fig. 3 of the drawing. The heel member 1 is then securely held in position on the heel supporting member 2 by means of the adhesive 4 as shown best in Figs. 3 and 4 of the drawing.

It will be noted that the angular relation of the recess portion $1a$ in the heel member 1 , with the heel supporting member 2 at the outer side provides secure and permanent fixed relation of the heel member 1 on the heel fastening member 2 when being worn on the footwear and walked upon in substantially the natural motion of walking as performed by the average person.

In the modification, as shown in Figs. 5 and 6 of the drawing, I have provided a modified heel supporting member $2b$ which is similar to the heel fastening member 2 and this member $2b$ is provided with welt portions $2c$ which are arranged to be positioned in conforming recess portions $1e$ in the modified heel member $1f$, as shown best in Fig. 5 of the drawing. It will be noted that these welt portions $2c$ are positioned around and extending outwardly from the outer side of the modified heel supporting member $2b$ and are provided with end portions $2d$ and $2e$ which are positioned in spaced relation from the corner portions $2f$ of the modified heel fastening member $2b$, as shown best in Fig. 6 of the drawing. It will be noted that the heel member $1f$ is arranged to be forced over the modified heel fastening member 2 and is arranged to be secured thereon by adhesive and by means of the conforming recess portion $1e$ on the outwardly extending welt portions $2c$ of the heel supporting member $2b$, as shown best in Fig. 5 of the drawing.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

1. In a footwear heel of the class described, the combination with the conventional footwear sole, of a heel supporting member secured to said sole at the heel portion thereof spaced from the side edge thereof and secured to the sole, a heel member provided with a recess conforming to said heel supporting member and fitted thereover against said sole, and the front and back sides of said supporting member being angular and extending downwardly and forwardly.

2. In a footwear heel of the class described, the combination with the conventional footwear sole, of a heel supporting member secured to said sole at the heel portion thereof spaced from the side edge thereof and secured to the sole, a heel member provided with a recess conforming to said

heel supporting member and fitted thereover against said sole, the front and back sides of said supporting member being angular and extending downwardly and forwardly, and the side walls of said support being angular and extending inwardly and downwardly.

3. In a footwear heel of the class described, the combination with a footwear sole composed of a single layer of leather at the heel portion, of a heel supporting member rigidly secured to said sole centrally at the heel portion provided with downwardly and forwardly arranged angular walls at its front and back sides and a resilient heel member provided with a conforming recess in its upper surface arranged to fit snugly and stretch over said supporting member.

4. In a footwear heel of the class described, the combination with a footwear sole composed of a single layer of leather at the heel portion, of a heel supporting member rigidly secured to said sole centrally at the heel portion provided with downwardly and forwardly arranged angular walls at its front and back sides, a resilient heel member provided with a conforming recess in its upper surface arranged to fit snugly and stretch over said supporting member, and an adhesive interposed between said heel member and said heel supporting member on all contacting surfaces.

5. In a footwear heel of the class described, the combination with a footwear sole composed of a single layer of leather at the heel portion, of a heel supporting member rigidly secured to said sole centrally at the heel portion provided with downwardly and forwardly arranged angular walls at its front and back sides, a resilient heel member provided with a conforming recess in its upper surface arranged to fit snugly and stretch over said supporting member, an adhesive interposed between said heel member and said heel supporting member on all contacting surfaces, and between the upper side of said heel member and said sole.

6. In a footwear heel of the class described, the combination with a footwear sole composed of a single layer of leather at the heel portion, of a heel supporting member rigidly secured to said sole centrally at the heel portion provided with downwardly and forwardly arranged angular walls at its front and back sides, a resilient heel member provided with a conforming recess in its upper surface arranged to fit snugly and stretch over said supporting member, said supporting member provided with a welt portion intermediate its upper and lower sides and said heel member provided with a conforming groove.

GEORGE W. COBB.
